UNITED STATES PATENT OFFICE.

TONY ZYGIEL, OF HAMILTON, ONTARIO, CANADA.

DUMP-CAR.

1,322,668.

Specification of Letters Patent. Patented Nov. 25, 1919.

Application filed March 15, 1919. Serial No. 282,800.

To all whom it may concern:

Be it known that I, TONY ZYGIEL, a citizen of Austria, residing at Hamilton, Prov. of Ontario, and Dom. of Canada, have invented a certain new and useful Improvement in Dump-Cars, of which the following is a specification.

This invention relates to improvements in freight cars and particularly to types adapted to convey coal, ore, broken rock and the like, having as its special object the provision of means whereby the load may be readily released from the car in an easy and convenient manner.

A further object is to provide a car having a floor capable of being inclined, facilitating the unloading of the contents.

A still further object is to provide a car having a barred or grate closure for the dumping end of the car, which is automatically released upon the depression of the floor.

These and other like objects are attained by the novel construction and combination of parts hereinafter described and shown in the accompanying drawings, forming a material part of this disclosure, and in which—

Figure 1 is a longitudinal sectional view taken substantially through the center of a car made in accordance with the invention.

Fig. 2 is an end view of the same, parts being broken away in order to disclose the construction.

Fig. 3 is a side elevation thereof.

Fig. 4 is an end view showing a modified form of car.

Fig. 5 is a fragmentary side elevational view of the same, and

Fig. 6 is a fragmentary perspective view showing the grate bar securing means.

In the drawings, the numeral 10 designates conventionally, ordinary types of wheels used upon the tracks of a railway, the same having extended between them axles 11, on which are mounted supports 12, carrying the frame of the car.

These support the side elements 14, disposed longitudinally of the car structure, from which rise standards 15, the same having at their upper ends top plates 16, and engaged therebetween, at the end is a cross-rail 17 while the other end wall 18 extends downward to the floor.

In the forms shown in Figs. 1, 2 and 3, the sides 20 are inclined, converging toward the center in which is a flooring 21, supported by hinge 19 at one end and having at the

other end a pair of eyes 22, engaged with cables 23 which extend over drums 24 mounted upon a transverse shaft 25, extending out from the rail 17 and provided with a manually operable handle 26. Secured adjacent to the handle 26 is a ratchet 27, a spring pressed pawl 28 engaging with its teeth so as to hold it in an adjusted position. By operating the handle 26, the cables 23 are wound upon the drums and the flooring elevated into a level position.

Obviously, by removing the detent pawl 28, the flooring drops, at which time staples 30, set in the outer extending end of the flooring are lowered releasing a plurality of vertical bars 32, these bars being formed with eyes 33 at the upper ends pivoting upon a short transverse bar 34, set immediately above the central opening 35 formed in the end wall, the bars constituting in effect a grating preventing the contents of the car from moving outward, however, when the flooring is depressed and the bars released, the material contained in the car is allowed to pass unrestrictedly out, due to the angular position of the floor at that time.

In the modification shown in Figs. 4 to 6 inclusive, the flooring 14 extends continuously throughout the length of the car the end of which contains an opening 36 covered by a lattice arrangement of bars 37, having eyes at their upper ends 38 pivoted upon a transverse bar 39, while their lower ends pass into staples 40, formed by crank-like extensions from a central shaft 41 rotatable in bearings 42 at its ends, one of its ends extending laterally from the surface of the car and is provided with an actuating handle 43 by which the cranks may be turned downward, freeing the vertical bars 37 so as to allow the contents of the car to move out.

From the foregoing it will be seen that an effective dumping device has been presented, especially applicable cars of the type described for carrying coal, crushed stone, ore and other like commodities which it is desired to dump in an expeditious manner and without the usual shoveling and labor ordinarily employed.

Having thus described my invention what I claim is new and desire to secure by Letters Patent, is—

A railroad car of the character described, comprising in combination, a hinged floor, a pair of eyes secured to one end of said floor, a transverse shaft, and drums on said

shaft, cables secured with their ends to said eyes and guided over said drums, a handle bar for operating said shaft, and a ratchet and pawl arrangement for holding the parts in their adjusted position, a plurality of vertical bars secured to the outer extended end of said floor, eyes at the upper ends of said

bars and a short transverse bar to which the upper ends of said bars are pivotally secured.

10 In testimony whereof I have affixed my signature.

TONY ZYGIEL.
